UNITED STATES PATENT OFFICE.

GEORG KRALL, OF MÜLHAUSEN, GERMANY.

MECHANISM FOR CLEANING COTTON AND LIKE FILAMENTS.

1,031,937.

Specification of Letters Patent.

Patented July 9, 1912.

Application filed April 17, 1908. Serial No. 427,711.

To all whom it may concern:

Be it known that I, GEORG KRALL, a subject of the German Emperor, residing at Mülhausen, in the Province of Alsace-Lorraine and Empire of Germany, have invented 5 a new and useful Improvement in Mechanism for Cleaning Cotton and Like Filaments, of which the following is a specification.

10 This invention relates to an improved grating for cotton cleaning machines, opening machines, and other like mechanism, especially designed for the preparing machines in the cotton spinning industry, and 15 the arrangement of which may be adjusted according to the requirements of the particular case. The adjustment may be made according to the quality of the cotton, the amount of moisture in the same during the 20 working, the efficiency of the ventilation, the arrangement of the dust channels and the dust collector, the thickness of material, the number and kind of the strikers to which the material is exposed and the speed 25 of rotation. All these points influence the efficiency of the cleansing and the opening up. The grating hereinafter described permits by reason of its special adjustability all these circumstances to be taken into account in each separate case, and secures the 30 best possible cleansing and opening up without damage to the staple and without loss of good filaments. This adjustment is attained by the following means: 1. The 35 number of bars can be increased or diminished according to need in the manner set forth. 2. The bars can be adjusted in relation to their distances apart with the greatest ease. 3. The inclination of the bars is 40 adjustable according to need in such a manner that the separate bars may receive consecutively a progressively greater or less inclination, whereby the efficiency of the grating is very considerably increased.

45 The drawing illustrates the invention as follows:

Figure 1 shows the arrangement of the grating in longitudinal section. Fig. 2 shows a section through the side support of the grating on the line A—B of Fig. 1. Fig. 3 shows a similar section on the line C—D of Fig. 1. Figs. 4 and 5 show details 50 of the construction.

Each of the two side supports of the 55 grating consists of a fixed part *a* and an adjustable part *b*. The ends of the bars rest

at both ends in the channel formed by the connection of the parts *a* and *b*. The fixed part *a* is firmly screwed to the cleaning frame. It possesses an upper limiting rim *c* 60 which is adjusted concentrically to the track of the striking organ *d* (shown in the drawing as a beater vane) so that the arc-shaped track formed by the upper edges of the bars has as its center the center of revolution *x* of the vane *d*. The movable part *b* is secured by means of screws *e* and *f* to the part *a*. The screws *g* and *h* and slots *i* and *k* provide for the adjustment and fixing of the part *b* in any requisite position. The 65 lower limiting ridge *l* of the arc-shaped recesses can in this way be adjusted eccentrically with regard to the upper limiting ridge *c*, so that the distance apart of the two ridges *c* and *l* is less at the point of 70 entrance of the filaments than at the point of exit, that is to say, at the lower end, or vice versa. By this progressive broadening of the recess in the one or the other direction, the bars *m* of the grating are obliged 75 progressively to diminish or increase their inclination to the imaginary radius directed to the center of revolution of the beating organ.

Between each of the separate bars *m* of 80 the grating, there is placed a little separating block *n* in the recess. These blocks are interchangeable and the several blocks vary in thickness from 4 to 12 millimeters, so 85 that the distance between the separate bars can be adjusted accordingly. The blocks 90 possess underneath each a heel piece projecting into the lower part of the recess, which prevents the block from falling out. The spacing blocks *n* may either extend entirely from end to end of the bars *m* or may 95 only be arranged at the ends of the said bars. The set screw *o* effects the pressing of the bars from the last bar to the first. On a metal piece *p* inserted after the last 100 bar *m* there is screwed fast a piece of sheet iron *q*, which closes the opening to the rear of the grating. In order to reduce the length of the grating requisite there is inserted between the last bar *m* and the set 105 screw *o* a metal piece *p* of corresponding length, in case the set screw *o* does not suffice for the attainment of this object. 110 In machines as hitherto constructed hacking bars or combs were used from 4 to 10 cm. width provided each with 4 to 8 rows of teeth, which could not serve as grating bars

and which prevented the most effective part of the grate from acting in the separation of impurities, without reference to the fact that the number of teeth was often too great and therefore acted injuriously. In the improved apparatus the number of rows of teeth can be varied according to requirement and the toothed bar is at the same time a grating bar, so that these drawbacks are avoided.

In Fig. 1 of the drawings, the three first bars where the fibrous material enters the apparatus are shown as provided with pins. Fig. 5 shows such a bar on a larger scale. This bar consists of a metal rod in which wire pins are mounted the projecting ends of which are ground or filed to a point.

The ribs *c* and *l* are arranged at varying progressive distances apart so that each bar is somewhat more inclined than the next. As each bar abuts against both the rib *c* and the rib *l*, then because of the increasing width of the support the inclination of each bar will vary with respect to the others.

What I claim is:

1. An adjustable grating for rotary cleaning mechanism for cotton and like filaments comprising in combination a bearing frame

forming an arc of a circle concentric with the axis of rotation of the rotary member, 30 a series of movable transverse bars in said frame, movable spacing blocks between the said bars and means for adjusting the lower part of the supporting frame relatively to the upper part thereof.

2. An adjustable grating for rotary cleaning mechanism for cotton and like filaments comprising in combination the fixed upper frame *a*, the lower part *b* adjustable with regard to the upper frame, the bars *m* supported at their ends between *a* and *b* and so that by the adjustment of *b* their position relatively to the rotary member of the machine is determined, the spacing blocks *n*, the covering plate *q* attached to the last bar *p*, and the set screw *o* adapted to maintain the bars and plate firmly in place, substantially as described.

In testimony whereof I have signed my name to this specification in the presence of two subscribing witnesses.

GEORG KRALL.
